UNITED STATES PATENT OFFICE.

CHARLES SCHULTZ, OF CHICAGO, ILLINOIS.

EXPLOSIVE-ENGINE.

No. 851,779.

Specification of Letters Patent. Patented April 30, 1907.

Application filed January 3, 1905. Serial No. 239,442.

To all whom it may concern:

Be it known that I, CHARLES SCHULTZ, a citizen of the United States, residing at Chicago, in the county of Cook and State of Illinois, have invented certain new and useful Improvements in Explosive - Engines, of which the following is a specification.

This invention relates to explosive engines, and refers particularly to means for altering the effective force of the explosion.

The invention also refers to the various improvements in detail hereinafter described.

In the present embodiment of the invention, the object first-mentioned is attained by opening the exhaust port in the explosion chamber at different points in the stroke of the piston. This result is accomplished by forming notches in a valve ring attached to the piston, of different depths with respect to the movement of the piston, and making said valve ring rotatable to bring any one of said notches into alignment with the exhaust port.

In the accompanying drawings, Figure 1 is a vertical central section taken through an explosive engine embodying the features of my invention. Fig. 2 is a horizontal sectional view taken on dotted lines 2 2 of Fig. 1. Fig. 3 is a similar view showing one of the exhaust notches in the valve ring registering with the exhaust port. Fig. 4 is a transverse sectional view through the sleeve for receiving the rod for turning the valve ring, also through said rod. Fig. 5 is a transverse sectional view through the cylinder and piston, showing the exhaust notches in the valve ring and the exhaust port in the cylinder. In this view the valve ring is in the same position as in Fig. 3. Fig. 6 is a transverse section through the piston and its oscillatory connection with the crank rod, taken on dotted line 6 6 of Fig. 1. This connection permits the oscillatory movement of the piston within the cylinder. Fig. 7 is a side elevation of said connection.

I have herein shown this invention as applied to a two-cycle gasoline engine, and referring to the drawings 1 designates the base of the engine, within which base is formed a chamber 2 for receiving the hydrocarbon gas. The cylinder 3 of the engine is formed integral with the base, and is provided with a water-jacket 4. Hydrocarbon gas is introduced into the receiving chamber 2 through the pipe 5 having a check valve 6 to prevent a receding movement of the gas therein, and

is conducted from said chamber to the cylinder by means of the pipe 7 or a port cored within the walls of the cylinder. Upon its opposite side the cylinder 3 is provided with an exhaust port 8, in this instance placed somewhat nearer the upper end of the cylinder than is usual in engines of this character. The upper end of the cylinder is closed by means of the cylinder head 9, which head is provided with a circular central opening 10, for receiving the tubular sleeve 11. A rod 12 square or of any other non-cylindrical form slides longitudinally within the central opening of said sleeve, being fitted closely within said opening. The lower end of the sleeve 11 has an outwardly extending annular flange 13 adapted to contact the inwardly extending ring 14 upon the head 9 and to fit tightly thereupon, as by means of a ground joint between said ring and said flange. At its upper end the joint between the rod 12 and the sleeve 11 is closed by means of stuffing box 15 of usual construction. The sleeve 11 and the rod 12 are rotatable within the cylinder 9 by means of a hand lever 16 fixed upon said sleeve.

A crank 17 and crank shaft 18 are suitably supported in bearings (not shown) in the base 1, the crank shaft extending through and the crank being wholly within the receiving chamber 2. A crank rod 19 has the usual connection with said crank 17 at the lower end of said rod, and at its upper end has a connection to permit the turning of the piston 20 with relation to the crank rod to be next described. The body portion of the piston 20 is tubular, and is provided with the usual packing rings 21 upon its peripheral face. Near its middle portion the piston is counter-bored as at 22, and a little distance below said counterbore has a shoulder 23. The upper end of the crank rod 19 has a wrist-pin 24, the outer ends of which are seated within segments 25 adapted to lie within the counterbore 22 and held in position therein by means of an interior ring-nut 26 having a screw-thread connection with said piston, said ring nut seating itself upon the shoulder 23 and preventing the withdrawal of said segments.

At its upper end the piston 20 has an integral upwardly extending annular valve ring 27 through which are cut a plurality of notches of different depths with relation to the longitudinal movement of the piston, which notches, by turning the piston, are

adapted to be placed in vertical alinement with the exhaust port 8. In this instance I have shown two notches 28 and 29 in said valve ring. In case it should be desirable not to rotate the piston, it is clear that the valve ring 27 might be made separate from, but attached to the piston and arranged to be rotated with relation thereto. The lower end of the rod 12 is secured rigidly to the piston 20 in any suitable manner, as by means of the ears 30 fixed upon said rod and the screws 31 passing through said ears and into the piston. Suitable means (not shown) may be provided for holding the piston or valve ring in any predetermined position.

32 refers to an igniter of any suitable construction adapted periodically to ignite the charge.

Access to the receiving chamber 2 is had by means of openings 33 and 34 through the opposite side walls of the base 1, and said openings in practice are closed by means of heads 35 and 36.

In operation, when it is desired to utilize the full efficiency of the explosive charge the valve ring 27 is turned so that neither of the notches 28 and 29 is in coincidence with the exhaust port 8 as the piston is reciprocated. When the valve ring is in this position said port is not uncovered until the piston approaches the lowest point in its stroke, when the upper edge of the ring 27 falls below the exhaust port, uncovering said port and permitting the escape of the dead gases. Upon its upward movement the piston draws into the receiving chamber 2, through the pipe 5, a quantity of hydrocarbon gas. Upon the downward movement of the piston the gas, being prevented from escaping from the receiving chamber 2 by reason of the check valve 6, is displaced and forced upward through the pipe 7 into the cylinder. Upon the upward movement of the piston the charge drawn into the cylinder is compressed, and when the piston starts on its downward movement said charge is exploded by the igniting mechanism 36. The piston is driven downward by the force of the explosion, pressure being exerted upon its upper side by the expanding gases until the exhaust port 8 is uncovered, when the gases within the cylinder are exhausted through said port. By turning the valve ring 27 and bringing the notch 28 into coincidence with the exhaust port, said port is uncovered earlier in the downward movement of the piston than when the valve ring is in the position shown in Fig. 1, and when said valve ring is rotated to bring the notch 29 into coincidence with the exhaust port, said port is uncovered still earlier in the downward movement of the piston, as shown in Fig. 3. When maximum speed and power are required, the valve ring is rotated into the normal position, as shown in Fig. 1. When an earlier exhaust with less

power is desired, the valve ring is rotated to bring either one of the notches 28 and 29 into coincidence with the exhaust port. In the normal position of the valve ring the power of an explosion is communicated through the crank rod to the crank through the full stroke of the piston. When the valve ring is rotated so that the notch 28 is in vertical alinement with the exhaust port 8 the force of the explosive charge is removed from the piston when said piston has traveled through about two-thirds of its reciprocatory movement, and when the notch 29 is in coincidence with the exhaust port said port is uncovered and the pressure of the exploded charge upon the piston is exhausted when the piston has traveled about one-half of its stroke

My invention is not restricted to the precise construction and arrangement of parts herein shown and described, as such construction and arrangement may be changed by those skilled in the art without departing from the spirit and scope of the invention.

I claim as my invention:

1. In an explosive engine, in combination, a cylinder having a port therein; a piston; and means moving with said piston for opening said port at various points in the stroke of said piston.
2. In an explosive engine, in combination, a cylinder having a port therein; a piston for said cylinder; means traveling with said piston for covering and uncovering said port; and means adapted to be actuated by the operator for varying the time of uncovering said port with reference to the position of the piston.
3. In an explosive engine, in combination, a cylinder having a port therein; a piston in said cylinder; a valve member on said piston adapted to open and close said port; and means for adjusting the position of said valve member with relation to said port, independently of the movement of said valve member due to said piston, for opening said port at various points in the stroke of the piston.
4. In an explosive engine, in combination, a cylinder having a port therein; a piston in said cylinder; a valve member on said piston adapted to open and close said port; and a rod connected with said valve member and extending to a point outside the cylinder and arranged to be moved by the operator for moving said valve member.
5. In an explosive engine, in combination, a cylinder having a port therein; a piston in said cylinder, said piston being provided with means for opening and closing said port; and means for adjustably rotating said piston to vary the time of opening said port.
6. In an explosive engine, in combination, a cylinder having a port therein; a piston in said cylinder, said piston being provided

- with means for opening and closing said port; a crank shaft; a connection between said piston and said crank shaft permitting of a rotation of said piston; and means for rotating said piston through variable distances to open and close said port at various points in the stroke of said piston.
7. In an explosive engine, in combination, a cylinder having a port therein; a piston in said cylinder; a valve member moving with said piston, said valve member being cut away at two different points with reference to the stroke of the piston; and means for adjusting said valve member to bring either of said cut-away points in position to register with said port.
8. In an explosive engine, in combination, a cylinder having an exhaust port therein; a piston in said cylinder; a valve ring fixed with relation to one end of said piston, said ring being notched at two different points with reference to the stroke of the piston; and means for rotating said piston to bring either of said notches in position to register with said exhaust port.
9. In an explosive engine, in combination, a cylinder having a port therein and an opening extending through one of its ends; a piston in said cylinder; a valve member fixed with relation to said piston, said member being cut away at two different points with reference to the stroke of the piston; a rod fixed to said valve member and extending through the opening in the end of said cylinder to a point outside of said cylinder; and means for rotating said rod.
10. In an explosive engine, in combination, a cylinder having a port therein and an opening extending through one of its ends; a piston in said cylinder; a valve member fixed to said piston for opening and closing said port; and means for adjusting the position of said valve member with relation to said port,
- said means comprising a rod of angular cross-section fixed to said member, a sleeve adapted to receive said rod and to lie in said opening in the end of said cylinder, and means for rotating said sleeve.
11. In an explosive engine, in combination, a cylinder having a port therein; a piston; and means in said piston controllable from without the cylinder, for opening said port at various points in the stroke of said piston.
12. In an explosive engine, in combination, a cylinder having a port therein; a piston for said cylinder; means traveling with said piston for covering and uncovering said port; and means adapted to be actuated by the operator from without said cylinder, for varying the time of uncovering said port with reference to the position of the piston.
13. In an explosive engine, in combination, a cylinder having a port therein; a piston in said cylinder, said piston being provided with means for opening and closing said port; means for adjustably rotating said piston to vary the time of opening said port, said means being operable from without said cylinder.
14. In an explosive engine, in combination, a cylinder having a port therein; a piston in said cylinder, said piston being provided with means for opening and closing said port; a crank shaft; a connection between said piston and said crank shaft permitting of rotation of said piston; and manipulative means for rotating said piston through variable distances to open and close said port at various points in the stroke of said piston, said means being operable from without said cylinder.
